UNITED STATES PATENT OFFICE.

HENDERSON P. CHILDRESS, OF NEW YORK, N. Y.

COTTON-PICKER.

No. 828,018.

Specification of Letters Patent.

Patented Aug. 7, 1906.

Application filed November 14, 1905. Serial No. 287,261.

To all whom it may concern:

Be it known that I, HENDERSON P. CHILDRESS, a citizen of the United States, residing at New York, in the county of New York and State of New York, have invented a new and useful Cotton-Picker, of which the following is a specification.

This invention relates to that class of pickers wherein a mechanical device is employed to detach the cotton from the boll and delivers it to suitable conveying means.

The principal object in the present case is to provide an improved device of the above character that will effectively pick the lint-cotton and will eliminate, to a very material degree, the danger of collecting sticks and other trash with the same.

Two embodiments of the invention are illustrated in the accompanying drawings, 20 wherein—

Figure 1 is a top plan view of one form of picking mechanism, the casings being shown in section. Fig. 2 is a side elevation of the same. Fig. 3 is a detail horizontal sectional view through the picking device. Fig. 4 is a vertical longitudinal sectional view through the structure. Fig. 5 is a top plan view of the other embodiment of the picking mechanism, the casings being also shown in section. Fig. 6 is a side elevation of the same. Fig. 7 is a detail horizontal sectional view through the picking device. Fig. 8 is a vertical longitudinal sectional view through the structure, and Fig. 9 is a detail perspective view of one of the rings or bands.

Similar reference characters designate corresponding parts in all the figures of the drawings.

In the embodiment illustrated in the first four figures a support is employed comprising spaced bars 5, to and between which is journaled a pulley 6. Around the pulley 6 passes a conveyer-belt 7, that is provided on its outer side with cotton-engaging teeth 8. Between the front ends of the supporting-bars 5 is located the picking device, which secures the cotton from the plant and delivers it to the teeth 8 of the conveyer-belt 7. This device in the present instance consists of a hollow drum having heads 9, journaled on stationary bearings 10, secured to the front ends of the bars 5, said drum having a peripheral wall 11, provided between its ends with an annular enlargement of greater diameter than the wall, said enlargement consist-

ing of a band or ring 12, that surrounds the drum and is free with respect thereto in order to permit the movement of the ring upon the drum. An axle 13 is mounted in the stationary bearings 10 in advance of and consequently eccentric to the axis of rotation of the drum. On this axle is mounted a hub member 14. Connected to the hub member 14 by means of pivot-pins 15 is a plurality of sets of picking-fingers 16, which fingers pass through guides 17, pivoted at their outer ends in the drum, and through the peripheral wall 11 of said drum. Certain of the fingers extend on opposite sides of the ring 12. Others pass directly through the ring.

The above-described picking apparatus is operated from the cotton-conveyer pulley 6 by any suitable means—as, for instance, gear-wheels 18, mounted on the drum and pulley and connected by an intermediate and intermeshing pinion 19. Casings 20, secured to the supporting-bars, cover the bearings for the pulley and drum, and one of said casings also incloses and protects the gearing.

The operation of the device may be briefly described as follows: The cotton-conveying belt 7 being operated from any suitable source of power will rotate the pulley 6, and, as a consequence, the picking-drum will also be revolved. The fingers as they pass around the front portion of the device will be projected and as they pass around the rear portion of the same will be withdrawn into the drum, as will be clear by reference to Fig. 4.

If, therefore, the picking device is presented to a boll, the projecting fingers will engage the cotton and detach the same from such boll, carrying it rearwardly to the teeth of the conveyer-belt 8. By reference to Fig. 3 it will be noted that while the central fingers of each set are completely retracted those on the opposite sides of said ring are not completely inclosed. The ring or band is left loose in order to allow for the peculiar movements of the outer ends of the fingers. The teeth 8, however, will remove the cotton from the picking device. If the teeth should engage a limb, stalk, or other objectionable device of the character, it will rest upon the band 12, and as the teeth passing through said band are completely retracted said limb or stalk will be released. This will be apparent by reference to Fig. 4, wherein a device of the character is shown at A. As a result, it will be clear that while the device is entirely

efficient for picking cotton, because of the arrangement shown, the quantity of trash gathered is materially reduced.

Another, and probably the preferred form of structure, is illustrated in Figs. 5 to 9. In this embodiment a support is employed comprising spaced bars 5^a, to and between which is journaled a pulley 6^a. Around this pulley passes the usual conveyer-belt 7^a, provided on its outer side with cotton-engaging teeth 8^a. Between the front ends of the supporting-bars 5^a is located the picking device. In this form of the invention the said device consists of the usual hollow drum having heads 9^a, journaled on stationary bearings 10^a, secured to the front ends of the bars 5^a, said drum having a peripheral wall 11^a. Instead of one band or ring a plurality of the same, 12^a, are employed, disposed in spaced relation and freely mounted upon the peripheral wall. An axle 13^a, located in the stationary bearings 10^a in advance of and consequently eccentric to the axis of rotation of the drum, supports a hub member 14^a. Connected to the hub member by means of pivot-pins 15^a is a plurality of sets of picking-fingers 16^a, which fingers pass through the usual guides 17^a, pivoted at their outer end in the drum, said fingers also passing through the annular bands or rings 12^a. It will be observed that the said bands or rings are provided with circumferential channels or grooves 18^a, through which the outer ends of the fingers operate. Suitable gearing 19^a connects the pulley 6^a with the drum, and casings 20^a, secured to the supporting-bars 5^a, cover the bearings, one of the casings also inclosing the gearing. The operation of this embodiment is substantially the same as that already described with the exception that as all of the fingers operate through the bands or guides and while their inner ends are disposed slightly in projecting relation even when the fingers are in their innermost positions they will be arranged in the grooves 18^a, and a stalk or limb engaged by said fingers when in their projecting relations will rest upon the annular flanges of the rings, so that the fingers will disengage therefrom when passing the forwardly-projecting teeth of the conveyer-belt.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

65 1. In a cotton-picker, the combination

with a rotatable stripping-drum having a peripheral wall and an outer enlargement on the circumferential portion of said wall, said enlargement being of less width than the length of the drum of a picking-finger carried by the drum and movable through the enlargement into and out of the drum. 70

2. In a cotton-picker, the combination with a rotatable stripping-drum having a peripheral wall and a peripheral band extending about said wall and of less width than the length of the wall, of a picking-finger carried by the drum and movable through the band into and out of the drum. 75

3. In a cotton-picker, the combination with a rotatable stripping-drum having a peripheral wall, of a band loosely journaled on the peripheral wall, and a picking-finger carried by the drum and movable through the band. 80

4. In a cotton-picker, the combination with a rotatable stripping-drum having a peripheral wall, of a band loosely surrounding the peripheral wall of the drum, and a series of fingers eccentrically mounted within the drum and extending through the band. 90

5. In a cotton-picker, the combination with a rotatable stripping-drum having a peripheral wall and a peripheral band extending about said wall and of less width than the length of the wall, said band having a circumferential groove, of fingers movable into and out of the drum through the band and extending through the groove. 95

6. In a cotton-picker, the combination with a rotatable drum, of a band or ring loosely surrounding the drum and having a circumferential groove forming flanges on opposite sides of the same, of a series of fingers eccentrically mounted within the drum and extending through the band or ring between the flanges. 100

7. In a cotton-picker, the combination with a rotatable stripping-drum having a peripheral wall provided between its ends with a portion of greater diameter, said portion being of less width than the length of the drum, of picking-fingers movable into and out of the drum through the peripheral wall and the enlarged portion thereof. 110

8. In a cotton-picker, the combination with a rotatable stripping-drum including a peripheral wall having a band thereon, of a plurality of cotton-picking fingers slideable through the band and through the peripheral wall on opposite sides of the band, means for securing the inner ends of the fingers eccentrically to the axis of rotation of the drum, and means for rotating the drum. 120

9. In a cotton-picker, the combination with a support having a pulley, of a conveyer-belt passing about the pulley, spaced bearings mounted on the support in advance of the pulley, a drum journaled on the bearings and having a peripheral wall, an annular 125

130

band or ring surrounding the peripheral wall and of less width than said wall, a hub secured to the bearings eccentrically of the axis of rotation of the drum, and picker-fingers 5 connected to the hub, said picker-fingers passing through the peripheral wall of the drum and the annular band or ring.

10. In a cotton-picker, the combination with a stripping-drum, of a plurality of fingers having their inner ends mounted in the drum eccentrically to the axis of movement thereof, guides for the fingers pivotally mounted on the drum, and a band extending around the drum and over the guides, said band being of less width than the length of the drum, and said fingers passing through the guides and band.

11. In a cotton-picker, the combination with a stripping-drum, of a plurality of bands 20 or rings surrounding the drum and of less width than the length of the same, and fingers movable into and out of the drum and passing through the various bands or rings.

12. In a cotton-picker, the combination 25 with a stripping-drum having a peripheral wall provided with transverse openings, of guides pivoted at their outer ends in the

openings, sets of fingers mounted at their inner ends within the drum eccentrically to the axis of rotation thereof, and bands loosely 30 surrounding the drum and extending over the guides, said fingers passing through the guides and bands.

13. In a cotton-picker, the combination with a stripping-drum, of a plurality of bands 35 or rings loosely mounted on and surrounding the drum, and fingers movable into and out of the drum and passing through the various bands or rings.

14. In a cotton-picker, the combination 40 with a stripping-drum, of a plurality of bands or rings loosely mounted upon and surrounding the drum, said bands or rings having annular grooves in their outer sides, and fingers movable into and out of the drum, said fingers passing through the various bands or 45 rings and through the grooves thereof.

In testimony that I claim the foregoing as my own I have hereto affixed my signature in the presence of two witnesses.
